UNITED STATES PATENT OFFICE

152,721

DESIGN FOR A VEGETABLE SLICER

Nathan K. Morris, Asbury Park, N. J.

Application April 13, 1948, Serial No. 145,679

Term of patent 14 years

(Cl. D89—1)

To all whom it may concern:

Be it known that I, Nathan K. Morris, a citizen of the United States of America, residing at Asbury Park, county of Monmouth, and State of New York, have invented a new, original, and ornamental Design for a Vegetable Slicer, of which the following is a specification, reference being had to the accompanying drawing, forming part thereof:

I claim:

The ornamental design for a vegetable slicer, as shown.

NATHAN K. MORRIS.
